US0D1084493S

(12) **United States Design Patent** (10) **Patent No.:** **US D1,084,493 S**
(45) **Date of Patent:** **** Jul. 15, 2025**

(54) **AEROSOL GENERATOR**

(71) Applicant: **NICOVENTURES TRADING LIMITED**, London (GB)

(72) Inventors: **Jared Aller**, Winston Salem, NC (US); **Christina Tapp**, Winston Salem, NC (US); **Kang Min Kim**, London (GB); **William Webb**, San Francisco, CA (US); **Vic Pramono**, Winston Salem, NC (US); **Yu Chuan Chang**, Shenzhen (CN)

(73) Assignee: **NICOVENTURES TRADING LIMITED**, London (GB)

(**) Term: **15 Years**

(21) Appl. No.: **29/877,666**

(22) Filed: **Jun. 9, 2023**

(30) **Foreign Application Priority Data**

Dec. 20, 2022 (EM) 015006724-0003

(51) **LOC (15) Cl.** **27-07**

CLAIM

The ornamental design for an aerosol generator as shown and described.

DESCRIPTION

FIG. 1 is a top front perspective view of an aerosol generator showing the claimed design;

FIG. 2 is a bottom rear perspective view thereof;

FIG. 3 is a bottom rear perspective view thereof;

FIG. 4 is a front view thereof;

FIG. 5 is a rear view thereof;

FIG. 6 is a top view thereof;

FIG. 7 is a bottom view thereof;

FIG. 8 is a left view thereof; and,

FIG. 9 is a right view thereof.

The broken lines in the drawings illustrate portions of the aerosol generator that form no part of the claimed design.

1 Claim, 9 Drawing Sheets
